(57) **CLAIM**

I claim the ornamental design of a cell phone mounting bracket, as shown and described.

DESCRIPTION

FIG. 1 is a perspective view of a cell phone mounting bracket showing the new design;

FIG. 2 is a front elevational view of the design of FIG. 1;

FIG. 3 is a rear elevational view of the design of FIG. 1;

FIG. 4 is a top plan view of the design of FIG. 1;

FIG. 5 is a bottom plan view of the design of FIG. 1;

FIG. 6 is a left side view of the design of FIG. 1;

FIG. 7 is a right side view of the design of FIG. 1;

FIG. 8 is a perspective view of a cell phone mounting bracket showing a second embodiment of the new design;

FIG. 9 is a front elevational view of the design of FIG. 8;

FIG. 10 is a rear elevational view of the design of FIG. 8;

FIG. 11 is a top view of the design of FIG. 8;

FIG. 12 is a bottom view of the design of FIG. 8;

FIG. 13 is a left side view of the design of FIG. 8; and,

FIG. 14 is a right side view of the design of FIG. 8.
